UNITED STATES PATENT OFFICE

THEODORE R. MITCHELL, OF WICHITA, KANSAS

SOUND REPRODUCING INSTRUMENT

Application filed April 3, 1929. Serial No. 352,305.

This invention relates to sound reproducing instruments and its general object is to provide a mounting and drive device for a turntable that is of a character whereby friction and vibration is reduced to a minimum and sound caused by the moving parts is practically completely absorbed before reaching the turntable, with the result true tone reproduced by the record is provided.

10 A further object of the invention is to provide a turntable for a sound reproducing instrument, that is of a weight to act in the nature of a fly wheel and has means for supporting and driving the same that not only 15 absorbs all extraneous sounds but is practically noiseless in its operation.

Another object of the invention is to provide a turntable drive that includes coil springs which function to drive the table 20 after the latter is started.

A still further object of the invention is to provide an improved turntable as well as a mounting and drive therefor, that together with the mounting and drive is primarily 25 designed for a reproducing instrument for talking pictures and which enables the instrument to provide clear and true reproductions.

A further object of the invention is to provide a device of the character set forth for reproducing instruments, that is extremely simple in construction, inexpensive to manufacture, easy to install, and efficient in operation and service.

35 This invention also consists in certain other features of construction and in the combination and arrangement of the several parts, to be hereinafter fully described, illustrated in the accompanying drawings and 40 specifically pointed out in the appended claims.

In describing my invention in detail, reference will be had to the accompanying drawings wherein like characters denote like or corresponding parts throughout the several views, and in which:

Figure 1 is a sectional view taken through my improved turntable and illustrating the 50 mounting and drive means therefor.

Figure 2 is a bottom plan view taken above the motor.

Figure 3 is a sectional view taken approximately on line 3—3 of Figure 1, looking in the direction of the arrows.

Referring to the drawings in detail, the reference numeral 1 indicates a motor or other driving means which is supported in the usual manner and includes a drive shaft 2.

Secured to the drive shaft intermediate its 60 ends and through the instrumentality of a pin 3 is a collar 4 which has extending from diametrically opposite sides thereof arms 5, and these arms have formed with their outer ends substantially U-shape members 6 that 65 rise therefrom as best shown in Figure 1 so as to dispose the arms of the U-shape members 6 in a position for a purpose which will be presently set forth.

The turntable which is indicated by the 70 reference numeral 7 includes a relatively thin top but has a relatively thick flange 8 depending from the periphery thereof and which adds materially to the weight of the turntable as will be apparent with the result 75 the turntable is in the nature of a fly wheel.

Depending centrally from the bottom of the top of the turntable is a hub 9 and extending between the hub 9 and the flange 8 are 80 reinforcing fins 10. Two opposed fins 10 are enlarged for a portion of their length at their connection with the hub 9 for the purpose of providing extensions 11 and these 85 extensions 11 are arranged in the path of the arms of the U-shape members as best shown in Figure 1.

The last mentioned fins are provided with openings adjacent their outer ends for the purpose of receiving one of the ends of coil 90 springs 12, while the opposite ends of said coil springs 12 are secured in openings formed in the arms 5 adjacent their outer ends.

The hub 9 is provided with a bore to accommodate the drive shaft 2, and disposed 95 between the outer end of the drive shaft 2 and the inner end of the bore is a ball 13 which of course acts as an anti-friction bearing. Rising from the center of the top of the turntable is a stud pin 14 which is adapted 100

to be passed through the central opening of a record A as shown, and the top of the turntable has secured thereto in the usual manner a disk B of felt for supporting the record as will be apparent. I have also shown 5 what is termed an electrical pick-up C which of course forms no part of the present invention but is used in reproducing instruments for talking pictures.

10 From the above description and disclosure of the drawings, it will be obvious that I have provided a device that not only efficiently drives the turntable of a reproducing instrument, but will reduce friction and vibration to a minimum as well as absorb extraneous sounds and sounds for moving parts 15 of the instrument before they reach the turntable which as shown is of a weight to act in the nature of a fly wheel, therefore it cooperates with the other elements of my device 20 to enable a reproducing instrument to reproduce true and clear tones.

25 In the operation of my device, the motor 1 is started in the usual manner, such movement causes the drive shaft 2 thereof to rotate the arms 5 together with their U-shape members, and one of the arms of each U-shape member will engage its extension 11 and thereby start the turntable which after it 30 has gained considerable momentum will free the extensions 11 from the arms of the U-shape members, with the result the drive thereafter will be through the instrumentality of the coil springs 12 and the extensions 35 11 will be disposed substantially midway between the arms of the U-shape members as shown in Figure 2 of the drawings.

40 It is thought from the foregoing description that the advantages and novel features of my invention will be readily apparent.

45 I desire it to be understood that I may make changes in the construction and in the combination and arrangement of the several parts, provided that such changes fall within the scope of the appended claims.

What I claim is:

1. In a reproducing instrument, a record 50 table, a record stud pin rising from the top of the record table, a hub depending centrally from the top and including a bore to loosely receive a drive shaft, a ball arranged in the bore between the drive shaft and inner end of the bore, and means for driving said record table from said shaft.

55 2. In a reproducing instrument, a turntable, a relatively thick flange depending from the periphery of the top of said turntable, a hub depending centrally from the top, reinforcing fins between the flange and hub, extensions formed with two opposed fins, means engageable with the extensions to initially move the turntable and resilient means between the initial moving means and the last mentioned fins for driving the turntable.

3. In a reproducing instrument, a record turntable, a relatively thick annular flange depending from the periphery of the top thereof, fins inwardly extending from the flange, a collar secured to a rotating driving means, arms extending from diametrically opposite sides of the collar, U-shape members secured to the outer ends of said arms, extensions formed with two opposite fins and arranged in the path of the arms of the U-shape members, and coil springs having their ends secured to the arms and last mentioned fins respectively for the purpose specified.

70 75 In testimony whereof I affix my signature.
